ANTICONCUSSION HELMET

Filed May 5, 1942

INVENTOR:
EMIL SELETZ.
BY *Martin O. Smith* ATTY.

UNITED STATES PATENT OFFICE
2,354,840
ANTICONCUSSION HELMET
Emil Seletz, Los Angeles, Calif.
Application May 5, 1942, Serial No. 441,796
2 Claims. (Cl. 2--6)

My invention relates to a head protective device in the nature of a helmet especially designed for the prevention of brain concussions due to shell shock, the heavy blasts of artillery and the guns on battleships and in forts, or in building and blasting operations which develop extreme noises.

Shell shock is not a psychoneurosis, but rather blast concussion of the brain produced by conduction vibration through the skull. This is confirmed by the fact that in fatal cases, punctuate hemorrhages may be found post mortem, not only in the meninges but even throughout the brain substance. Blast concussion may also produce nerve deafness, with or without injury to the ear drum, in the same manner that anesthesia is produced in the fingers of laborers as the result of the vibration developed by continued use of pneumatic hammers and like tools.

It is one of the principal objects of my invention to provide a relatively simple, practical and inexpensive sound proof helmet which will be highly effective in preventing blast vibrations and the like from reaching the brain, and the helmet according to my invention, is constructed so as to cover the entire calvarium and extends in front, downwardly over the forehead to the eye brows, the sides covering the ears, and at the rear, extending downwardly over the neck so as to afford a substantial degree of protection to the soft tissues and great vessels therein.

Further objects of my invention are to construct a concussion protective helmet composed of hard plastic material with a vacuum chamber which, in addition to rendering the helmet buoyant, effectively prevents the transmission of vibrations incident to heavy blasts, also serving as a non-conductor of heat and cold, further, to provide the helmet with a cushioning pad that fits directly against the head, neck and ears of the wearer so as to afford a maximum degree of comfort to the wearer, and further to combine with the helmet a small mask of flexible material such as rubber or plastic, which fits over the nose and mouth and said mask being provided with a screened opening which permits normal breathing of the wearer, but effectually preventing an abnormal inrush of air through the nose and mouth to the inner ear.

With the foregoing and other objects in view, my invention consists in certain novel features of construction and arrangement of parts which will be hereinafter more fully described, claimed and illustrated in the accompanying drawing in which:

Fig. 1 is a perspective view of a helmet constructed in accordance with my invention and showing the same in position upon a wearer's head.

- 5 Fig. 2 is a vertical section taken approximately on the line 2--2 of Fig. 1 with the helmet removed from the head.
- 10 Fig. 3 is an enlarged horizontal section taken approximately on the line 3--3 of Fig. 1.
- 15 Fig. 4 is an enlarged horizontal section taken on the line 4--4 of Fig. 1.
- 20 Fig. 5 is a transverse section taken approximately on the line 5--5 of Fig. 1.
- 25 Fig. 6 is a vertical section similar to Fig. 2 and showing a modified construction.

Referring by numerals to the accompanying drawing, which illustrates a preferred embodiment of my invention, 10 and 11 designates respectively the outer and inner walls of the main body of the helmet, said walls being spaced apart to form a chamber 12 from which the air is exhausted to produce a vacuum. This main body portion of the helmet is substantially semi-spherical in shape so as to entirely cover the vertex and the front portions 13 of the spaced walls are extended downward to a point just above the eye brows so as to afford coverage and protection to the wearer's forehead. From the sides of the main body of the helmet, the spaced walls are extended downwardly as designated by 14 so as to cover and afford protection to the wearer's ears and the rear portions of said walls are extended downwardly and curved outwardly as designated by 15 to cover and provide protection for the back of the wearer's neck. The main body of the helmet as just described may be composed of any strong, hard material, light weight and buoyant, for instance, any of the plastics now in general use.

40 Suitably secured to the lower portion of the inner wall 11 of the helmet adjacent the lower edge thereof is a continuous pad 16 of suitably buoyant cushioning material, for instance, treated fiber, sponge rubber or the like, and from the 45 rear portions of the sides of this pad, tapered portions 17 extend downwardly so as to entirely cover the ears of the wearer. These portions 17 decrease in width and thickness so as to form straps 18 which pass beneath the wearer's chin, and 50 straps may be provided with conventional fastening means, such as a buckle 19, or with the complementary members of a snap fastener.

A small mask 20 composed of soft flexible material, such as rubber, is shaped so as to fit snugly 55 over the wearer's nose and mouth, and formed

in the lower portion of this mask is a small opening 21, in which is seated a fine mesh screen 22 of wire or the like. Thus, when the mask is applied for use, the mouth and nasal openings are entirely covered but normal breathing is permitted by the screened opening 21, and at the same time, such opening prevents any abnormal inrush of air as the result of blasts or heavy explosions. This mask is secured to the sides 17 of pad 16 by suitable straps 23, which pass across the wearer's cheeks.

My improved helmet being composed of hard plastic material, or the like, affords a certain degree of protection for the wearer's head against projectiles, such as small bullets and shrapnel, but the principal protection afforded is against heavy blasts, concussions or the like which, in many instances result in so-called "shell shock" concussion of the brain.

The helmet is light in weight and being provided with a vacuum chamber, effectually prevents the transmission of vibration to the wearer's brain, and this protection is materially increased due to the fact that when the helmet is in proper position upon the head, a substantial space is provided between the vertex and the helmet by reason of the cushioning pad 16 which extends entirely around the inner surface of the lower portion of the helmet. Further, the vacuum chamber provides an effective non-conductor for heat and cold, and thus the helmet may be comfortably worn in both tropic and frigid zones.

Inasmuch as the helmet is buoyant, it may serve as a life preserver by maintaining the wearer's head above the surface of the water.

By producing the helmet body from light colored plastics or the like and polishing the outer surface of the outer wall 10, the helmet will, to a considerable extent, reflect light rays and, there-

fore, it may be readily observed for a considerable distance by rescue parties seeking persons swimming or floating on the surface of the water.

In Fig. 6, I have shown a modified construction wherein a substantially semi-spherical shell 25 formed in a single piece from thin hard metal, is removably positioned on the upper outer portion of the outer wall 10 of the helmet body and being detachably retained thereon by readily releasable fastening means 26, the latter being secured to wall 10, preferably, on the front and rear of the helmet. This shell when removed provides a receptacle which may be used for drinking purposes, as a utensil for heating or cooking food, or for bailing water from a small boat.

Thus, it may be seen that I have provided an anti-concussion helmet and mask which is relatively simple in construction, inexpensive of manufacture and very effective in performing the functions for which it is intended.

It will be understood that minor changes in the size, form and construction of the various parts of my improved helmet and mask may be made and substituted for those herein shown and described without departing from the spirit of my invention, the scope of which is set forth in the appended claims.

I claim as my invention:

1. The combination with a substantially semi-spherical helmet provided in the greater portion of its outer surface with a shallow recess, of a cup shaped protective member of thin hard metal removably seated in said shallow recess with the outer surface of said cup-shaped member flush with the surface of the helmet outwardly from the recess therein.

2. The combination as set forth in claim 1 including readily releasable means for securing said protective member to said helmet.

EMIL SELETZ.
